ELECTRO-OPTICAL DEVICE

George A. Morton, Audubon, N. J., assignor to
Radio Corporation of America, a corporation of
Delaware

Substituted for abandoned application Serial No.
55,957, December 24, 1935. This application
March 4, 1937, Serial No. 128,976. In France
October 28, 1936

5 Claims. (Cl. 250—153)

This application is based on application Serial
No. 55,957, filed December 24, 1935 and is a sub-
stitute therefor.

5 This invention relates to electro-optical de-
vices and particularly to improvements in
electron-lens systems for electron-telescopes and
the like.

10 It is known to those skilled in the art to which
this invention appertains that electrons may be
subjected to a focusing action similar to that
achieved in optics with ordinary lens systems.
Electron focusing may be produced by subject-
ing the electrons in their travel to the influence
of an electro-static field or fields whereby their
15 trajectories are altered.

20 An electron-lens may be constituted, for ex-
ample, by a bi-part conduit or cylinder of uni-
form cross-section through which the electrons
travel from their source to their target or ter-
minal electrode. The "optical center" of such a
25 lens is adjacent the space intermediate the cylin-
der sections.

As described in copending application Serial
No. 46,644 to George A. Morton, filed October 25,
25 1935, when the hollow conduit members are
properly proportioned, a sharp image of unity
magnification may be achieved in accordance
with the general formula

$$30 \quad m \approx \frac{v}{2u}$$

where m is magnification, v is the distance from
the optical center of the lens to the target and u
35 is the distance from the optical center to the
electron source.

Substantially, the same general formula holds
true where, as in certain electro-optical devices,
a series of ring-like electrodes are substituted
40 for one of the cylinder sections for the purpose
of rendering the focus of the lens electrically
adjustable. Such an arrangement is described
in connection with Fig. 2, copending application
Serial No. 38,380 to Leslie E. Flory and George A.
Morton, filed August 29, 1935.

45 An object of the present invention is to pro-
vide an electro-optical system wherein magnifi-
cation may be equal to, greater than, or less than
unity irrespective of the exact length of the
members constituting the electro-optical system.

50 Another object of the invention is to standard-
ize the construction of electron telescopes and
the like whereby parts of standard dimensions
may be employed in electro-optical devices de-
signed to exhibit different fixed ratios of magnifi-
cation.

Another object of the invention is to reduce
the voltage difference necessary between elements
of an electron lens.

Another object is to provide an electron lens
structure capable of removing, or otherwise ob-
viating the effects of, stray electrons.

10 The above and other objects are accomplished
in accordance with the present invention by pro-
viding the device with an electron-lens con-
stituted by a pair of spaced-apart electrodes
having each an orifice of a diameter less than
that of the other apertured electron-directing
members.

15 If these orifices are of unequal diameter, the
magnification ratio will be other than that
dictated by the physical length of the system;
the actual ratio depending primarily upon the
relative arrangement of the lens elements. This
phenomenon obtains by reason of the different
20 distribution and the different radii of curvature
assumed by the equipotential lines of force about
the lens elements.

25 If the orifices are of similar diameter, the
voltage difference necessary to achieve a desired
ratio of magnification is less than that required
in electro-optical systems wherein all of the aper-
tured elements are of the same diameter. With
30 a pair of similar orifices of reduced diameter, a
smaller voltage difference may be employed to
maintain a symmetrical distribution of electro-
static lines of force since the area embraced by
the field is smaller.

35 While the invention will be disclosed as em-
bodied in an electron-telescope, it is not to be
limited by such application as the disclosure in
this respect is merely illustrative for purposes of
explaining the inventive concept.

40 Figure 1 is a diagrammatic sectional view of
an electron telescope embodying an electron-lens
within the invention; the diameter of the orifices
constituting the lens being of similar size and
adapted to produce a symmetrical electrostatic
field thereabouts;

45 Fig. 2 is a diagrammatic sectional view of a
similar device wherein the orificed electrodes are
of unequal diameter and so arranged that

$$m > \frac{v}{2u}$$

and

50 Fig. 3 is a diagrammatic sectional view of a
similar device wherein the orificed electrodes are
of unequal diameter and so arranged that

$$m < \frac{v}{2u}$$

55

Like reference characters represent the same or corresponding parts in all figures.

In Fig. 1, a lens system within the invention is shown as applied to an electron telescope contained in a preferably highly evacuated container 1. A semi-transparent photosensitive cathode 3, curved to correct for curvature of the image field and for so-called "pin cushion" distortion is disposed adjacent to the leading end of the tube 1. A preferably inverted optical image of an object, not shown, is focused upon this curved photosensitive cathode 3 by means of a suitable lens system exemplified in the drawing by the single lens 7. Such optical lens system may be constructed of optical glass if the device 1 is to be used for examining visible images, or quartz if ultra-violet light from an object is to be utilized, or of hard rubber or the like if use is to be made of infra-red light.

Disposed adjacent to, or as shown in Fig. 1, forming part of the opposite end of the tube 1, is a semi-transparent fluorescent screen 9 of willemite or other suitable material upon which electrons from cathode 3 eventually impinge to form an externally visible re-inverted image.

If the electron image is to be utilized for television transmission, the fluorescent screen 9 may be dispensed with and the image may be directly scanned, for example, as shown in Farnsworth U. S. Patent No. 1,773,980, or it may be thrown upon a planar mosaic electrode which is, in turn, scanned by a cathode ray from an electron gun to provide a train of electrical impulses, as described in the Flory and Morton application previously mentioned.

The other electrode elements in the tube are designated 11a, 11b, 11c, 11d, 11e, 13e and 13. They are preferably symmetrically arranged in the order shown about the long axis of symmetry 40 of the container 1 so that they form a multi-part conduit between the terminal surfaces 3 and 9. Electrodes 11e and 13e are provided with flanges 11f and 13f which extend inwardly in spaced face-to-face relation. These flanges 11f and 13f are provided with similar aligned apertures 11g and 13g. The ring-like members 11 are the focusing electrodes and serve to direct the electrons toward the reduced apertures 11g and 13g from whence they are accelerated by the positively charged tubular anode 13 towards the screen 9.

As indicated in the drawing, the metal surfaces 11f and 13f surrounding orifices 11g and 13g are electrically and mechanically united, respectively, to the focusing electrode 11e and to the anode or accelerating electrode 13. If desired, however, they may be separate disc-like members. The exact dimensions of these equal apertures will depend upon the degree of magnification required, the lower limit in size being determined by the ability to direct the electrons from the cathode therethrough without impinging against the surrounding metal. Electrons which may be released by impact of stray electrons from the cathode 3 against the inner surface of the focusing electrodes will be arrested by that surface of the inwardly directed member 11f which is on the side of the cathode.

The anode or accelerating electrode 13 is in the form of an elongated open-ended cylinder formed either of solid conductive material or of a foraminous metallic sheet.

The relative potential distribution among all of the focusing electrodes 11 is the same regarding less of the sharpness of the focus required so

that, if desired, individual resistors 12a-12e may be permanently connected within the tube, for instance in the manner shown in copending application, Serial No. 48,982, to Zworykin, et al., filed October 30, 1935. These resistors are of such value as to supply the several electrodes 11 with separate potentials each of increased magnitude with respect to its next preceding electrode.

With the resistors 12 included within the tube, but three external leads are required. These leads 10 are connected to a suitable source of current exemplified in the drawing by the battery A and by the potential divider A1. The cathode 3 is preferably connected to the negative terminal and the anode 13 and the electrode 13e, integral therewith, to the positive terminal of the direct current source by leads 3' and 13', respectively. Adjustable lead 11' supplies operating potentials for all of the electrodes 11, the necessary distribution obtaining by reason of the resistors 12 previously described.

Alternating, instead of direct, current may be employed if desired, provided the alternations are at a rate sufficient to ensure persistence of vision.

Operation of the device of Fig. 1 is characterized by the presence of a substantially symmetrical family of equipotential surfaces about the reduced orifices 11g and 13g. As indicated by the dotted lines 11h and 13h, the contour of these surfaces corresponds to the outline of a bioconvex optical lens having opposite surfaces of the same radii of curvature.

The device of Fig. 2 is similar in all respects to that of Fig. 1 except that the reduced apertures, here designated 21g and 23g, respectively, are of unequal diameter, the larger orifice 21g being on the cathode side of the lens. This results in different radii of curvature on opposite sides of the lens and a shift in the equipotential surfaces 21h-23h so that the effective electron lens is moved closer to the cathode with a resultant increase in magnification.

In Fig. 3, the orifice 33g on the anode side of the lens is of a greater diameter than the orifice 31g on the cathode side. Here, as indicated by the dotted line 33h, the shift in the equipotential surfaces is more pronounced on the side of the direction of electron travel so that, the tube being otherwise the same as the tubes of Figs. 1 and 2, the effective electron-lens is moved closer to the screen 9 with a resultant decrease in magnification.

The electron-lenses of the devices illustrated by Figs. 1, 2 and 3 are each designed to achieve a single ratio of magnification. They may, however, be rendered capable of producing electron-images of various desired degrees of magnification by providing an adjustable lead from one of the small orificed electrodes and a separate lead to the focusing ring-like electrodes. In this case, the internal resistor 12e connecting the focusing electrodes and the selected magnifying electrode (say 11e, Fig. 1) is dispensed with. Such modification is deemed within the scope of copending application Serial No. 52,289 to George A. Morton, filed November 30, 1935.

While the series of focusing rings (11 Fig. 1, for example) are shown as separate and connected at different points to the voltage divider 12 it is, of course, apparent that the surfaces 11 may be made continuous. In this case the surface 11 will of itself provide the different voltages due to the voltage gradient between the ends thereof. A surface of this character may be formed as a thin sputtered high resistance con-

ducting film upon the inside wall of the glass envelope or even a separate cylinder positioned within the main envelope with appropriate connections made at its ends to a voltage source. 5
In another form the surface through which the voltage drop takes place to provide the effect of the series of rings 11 shown may be a carbon composition, such, for example, as that known and used in carbon resistors. 10
As a number of possible embodiments may be made of the above invention, and as changes may be made in the embodiments described without departing from the spirit and scope of the invention, it is to be understood that the foregoing is to be interpreted as illustrative and not in a limiting sense except as required by the prior art and by the appended claims. 15

What is claimed is:

1. In an electro-optical system, a photosensitive cathode adapted to release a family of electrons in response to the impression of a light image thereon, a screen, a conduit intermediate said cathode and screen through which said electrons pass to form an electron image on said screen corresponding to said light image, said conduit comprising a plurality of apertured members, the apertures in two adjacent of said members being each of a diameter less than that of the other members. 25

2. The invention as set forth in claim 1 wherein the diameters of the apertures in said two adjacent members are substantially the same. 5

3. The invention as set forth in claim 1 wherein the diameter of the aperture in that one of said two adjacent members which is nearer the cathode is greater than the diameter of the aperture in the other of said two adjacent members. 10

4. The invention as set forth in claim 1 wherein the diameter of the aperture in that one of said two adjacent members which is nearer the screen is greater than the diameter of the aperture in the other of said two adjacent members. 15

5. In an electro-optical system, a photosensitive cathode adapted to release a family of electrons in response to the impression of a light image thereon, a screen, a conduit intermediate said cathode and screen through which said electrons pass to form an electron image of fixed magnification on said screen corresponding to said light image, and apertured electrode means interposed in said conduit for rendering the fixed magnification of said system other than that dictated by the physical length of said conduit. 20 25

GEORGE A. MORTON.
